(57) **CLAIM**

The ornamental design for a light strip connector as shown and described.

DESCRIPTION

FIG. 1 is a top isometric front view of a light strip connector in accordance with the present invention;

FIG. 2 is a bottom isometric rear view of the light strip connector illustrated in FIG. 1;

FIG. 3 is a top plan view of the light strip connector illustrated in FIG. 1;

FIG. 4 is a bottom plan view of the light strip connector illustrated in FIG. 1;

FIG. 5 is a first side view of the light strip connector illustrated in FIG. 1;

FIG. 6 is a second side view of the light strip connector illustrated in FIG. 1;

FIG. 7 is a front end view of the light strip connector illustrated in FIG. 1; and,

FIG. 8 is a rear end view of the light strip connector illustrated in FIG. 1.

The broken lines in the figures show portions of the light strip connector for reference only and form no part of the claimed design.

1 Claim, 3 Drawing Sheets
